LOOM SHUTTLE

Isaac Snow, Lawrence, Mass., assignor to Draper Corporation, Hopedale, Mass., a corporation of Maine

Application October 30, 1936, Serial No. 108,424

3 Claims. (Cl. 139—215)

The present invention pertains to automatically threading loom shuttles, and more particularly to tension devices thereof.

Shuttles of the type to which my invention pertains have been provided with a plurality of fixed tensioning members such as pins arranged in two series in a longitudinal thread passage in the threading block. Such members are staggered in a manner to cause the filling thread to follow a tortuous course through the thread passage, whereby the filling thread is tensioned before it leaves the shuttle. Prior tension devices of this nature have not proven satisfactory, because such devices formed from separate individual pins are expensive and the pins cannot be readily replaced when they become worn.

It is a principal object of the present invention to provide, in a shuttle having a threading block provided with a longitudinal thread passage, a tension device formed from a single piece of sheet material and provided with two series of integral thread tensioning fingers fixed in the thread passage in staggered relation for engaging and tensioning the filling thread.

A further object of the invention is to provide, in a shuttle having a threading block as aforesaid, thread tensioning fingers in the thread passage, which fingers shall have wider thread engaging surfaces at the top of the thread passage than at the bottom thereof, whereby more tension is imparted to the filling thread when it is at the top of the thread passage than when it is at the bottom of the thread passage.

The foregoing and other objects of the invention are accomplished by the embodiment illustrated on the accompanying drawing, of which:

Fig. 1 is a plan view of the thread delivery end of a shuttle having my invention applied thereto;

Fig. 2 is a view of the threading block and tension device, in cross-section taken approximately on line 2—2 of Fig. 1; and

Fig. 3 is a view in cross-section taken approximately on line 3—3 of Fig. 2.

The shuttle shown on the drawing comprises a shuttle body 1 having a cavity 2 for reception of a filling carrier 3. The filling carrier is detachably held in the shuttle body by any suitable usual means, not shown. The shuttle body is recessed to receive a suitable threading block 4. The threading block 4 has front and rear walls 5 and 6 and a floor 7, defining the usual longitudinal thread passage 8. The threading block also has a horn 9 which projects from the front wall outwardly and rearwardly over the thread passage.

A side delivery eye 10 in the front wall of the

shuttle communicates with the thread passage.

The shuttle as thus far described operates in the usual manner, which may be briefly described. When the shuttle is first picked after the transfer thereto of a fresh filling carrier, the filling end 7 leading from the filling carrier swirls about in unwinding from the filling carrier, and passes beneath the horn 9 into the thread passage 8. During this first pick after transfer, the filling thread extends generally longitudinally of the shuttle, as shown by Fig. 1, well up toward the top of the thread passage. On the next pick, the filling thread passes down into the side delivery eye 10 and is thereby drawn down toward the bottom of the thread passage. The filling thread then continues to run over the floor of the thread passage, or over a wear pin 11 just above the floor.

The tension device of the present invention is of the type having two series of thread engaging fingers positioned in the thread passage 8. In accordance with the invention, the device is stamped or otherwise formed from one piece of sheet material such as metal. In the particular form shown on the drawing, the tension device has a longitudinal base portion 12 which is positioned in a slot 13 in the floor 7. This base portion is fixed in the slot in any suitable manner. I prefer, however, to provide a downwardly extending lug 14 on the portion 12, which lug is apertured to receive a screw or the like which may pass through the opening 15 in the threading block. The tension device includes two series of thread tensioning fingers 16, 16 and 17, 17, respectively.

The fingers 16 and 17 are formed integrally with the longitudinal portion 12 and project upwardly therefrom approximately centrally of the longitudinal thread passage. The fingers of the respective series are staggered in that the thread engaging surfaces of the fingers 16 are the rear vertical faces of such fingers and are materially rearwardly of the thread engaging surfaces of the fingers 17. The fingers are spaced apart longitudinally of the shuttle the distance necessary to provide the required tension on the filling thread. The tops of the fingers 16 are bent forwardly and inserted in a slot 18 in front of the threading block. The tops of the fingers 17 are bent rearwardly and inserted in a slot 19 in the rear wall of the threading block. This bending of the tops of the fingers provides a thread entrance which opens upwardly to receive the filling thread as the latter moves down into the thread passage.

The tension device as thus constructed is found to be as efficient as prior art constructions com-

prising two series of separate individual pins fixed in about the same relative positions as the present fingers 16 and 17. In addition, my tension device is much less costly than the individual pins. Furthermore, the one-piece tension device may be detachably secured to the threading block, as shown, whereby it may be readily replaced at small cost whenever it becomes worn.

The present invention also contemplates provision of means in the tension device for equalizing the tension on the filling thread during the first pick after transfer. That is, during such first pick the tension on the filling thread is usually less than during subsequent picks, because the additional friction incident to the passing of the thread to the side delivery eye is not present during the first pick after transfer. It is also noted that during the first pick the filling thread runs adjacent the top of the thread passage (see Fig. 3) while during subsequent picks the filling thread runs close to the bottom of the thread passage. I accordingly make the thread engaging surfaces of at least some, but preferably all, of the fingers 16 and 17 materially wider at the top of the thread passage than at the bottom thereof. The tension device thus imparts to the filling thread more tension during the first pick than during subsequent picks, with the result that the total tension of the thread is substantially the same during all picks.

Having fully disclosed the preferred embodiment of my invention, I claim:

1. An automatically threading loom shuttle comprising a shuttle body having a threading block and a side delivery eye, said threading block having a longitudinal thread passage, and a one-piece sheet-material tension device fixed to said threading block in said thread passage; said tension device comprising a longitudinal portion fixed in a slot at the bottom of said thread passage and two series of thread tensioning fingers formed integrally with said longitudinal portion and projecting upwardly therefrom in fixed staggered relation, the tops of the fingers of one

series being bent toward the front of the thread passage and the tops of the fingers of the other series being bent toward the back of the thread passage to provide an upwardly opening thread entrance.

2. An automatically threading loom shuttle comprising a shuttle body having a threading block and a side delivery eye, said threading block having front and rear walls and a floor defining a longitudinal thread passage, and a one-piece sheet metal tension device detachably secured to said threading block in said thread passage; said tension device comprising a longitudinal portion fixed in a slot in said floor and two series of thread tensioning fingers formed integrally with said longitudinal portion and projecting upwardly therefrom in fixed staggered relation, said fingers being spaced apart longitudinally of the thread passage, the tops of the fingers of one series being bent forwardly and inserted in a slot in said front wall and the tops of the fingers of the other series being bent rearwardly and inserted in a slot in said rear wall to thereby provide an upwardly opening thread entrance.

3. An automatically threading loom shuttle comprising a shuttle body having a threading block and a side delivery eye, said threading block having a longitudinal thread passage, and a one-piece sheet-material tension device fixed to said threading block in said thread passage; said tension device comprising a longitudinal portion fixed in a slot at the bottom of said thread passage and two series of thread tensioning fingers formed integrally with said longitudinal portion and projecting upwardly therefrom in fixed staggered relation, the thread engaging surfaces of at least some of said fingers being materially wider adjacent the top of the thread passage than at the bottom thereof to thereby impart to the filling thread more tension when it is at the top than when it is at the bottom of the thread passage, the tops of said fingers being curved to provide an upwardly opening thread entrance.

ISAAC SNOW.
